UNITED STATES PATENT OFFICE.

ALEX G. HUHN, OF MINNEAPOLIS, MINNESOTA, ASSIGNOR TO A. HUHN MANUFACTURING COMPANY, OF MINNEAPOLIS, MINNESOTA, A CORPORATION.

APPARATUS FOR DRYING OR COOLING MATERIAL.

Application filed November 18, 1925. Serial No. 69,774.

My invention relates to apparatus for drying or cooling material and more particularly material in a finely divided condition such as flour and starch which has a tendency to cling to heated or chilled surfaces and thus become scorched or unduly chilled thereby. An object of the invention is to prevent the possibility of any of the material being treated from lodging or remaining on the substantially horizontal tubes which I employ and thereby being subjected to an excessive action of the heating, cooling or freezing agents used within the tubes. I accomplish the objects of my invention by providing a cleaning mechanism which reciprocates along the tubes in engagement with the outer surfaces thereof and thereby continuously removes the material substantially as fast as it accumulates thereon.

20 The full objects of my invention will appear in connection with the detailed description thereof and the novel features embodied in my inventive idea will be particularly pointed out in the claims.

25 In the accompanying drawings which illustrate a practical embodiment of my invention,—

Fig. 1 is a view of the apparatus in central longitudinal section. Fig. 2 is a front elevational view. Fig. 3 is a rear elevational view. Fig. 4 is a view in section on the line 4—4 of Fig. 6. Fig. 5 is a view in section on the line 5—5 of Fig. 1. Fig. 6 is a fragmentary view showing a cover in top plan. 35 Fig. 7 is a detail view of a portion of the cleaning or scraping device. Fig. 8 is a view in section on the line 8—8 of Fig. 9. Fig. 9 is a view in section on the line 9—9 of Fig. 8. Fig. 10 is a view in section on the line 10—10 of Fig. 8.

40 Referring to the embodiment of the invention shown in the drawings, a battery of parallel tubes 11 are all supported at one end by securing them to a head 12 and are supported at the other end by extending a few of the tubes, as indicated at 16, and securing these extended tubes to supporting means carried by a casting 14. Within the tubes 11 and spaced from the walls thereof are smaller tubes 17, which as shown in Fig. 1, pass through the head 12 into a supply box 18 to which a heating or cooling agent is supplied by a pipe 20. The outer tubes 11, which are closed at their front ends, have their 45 rear ends leading into a discharge box 22

from which the heating or cooling agent is withdrawn through a pipe 24. Attached to the head 12 is a forwardly-extending rim 26 from the bottom of which a discharge pipe 28 extends, and from the top of which there 50 extends a pipe 30, which may be connected to a suction device or fan in the usual manner for drawing air through or from a casing or cylinder 32 which envelopes the tubes 11 and is rotatably supported upon rollers 34 55 which engage rings 35 placed around the casing as shown in Fig. 1. The casing is rotated by means of an annular gear 36 secured thereto at the front and driven by a spur gear 37 secured to a shaft 38 to which is also 60 secured a driving pulley 39. The interior of the casing 32 is provided with a plurality of flights 40, and in use the casing is preferably inclined downwardly from the inlet to the outlet end. The rear of the casing 32 65 makes a tight joint with the rim 26 and the front of the casing is partly closed by an annular plate 42 whose inner margin bears rotatably upon a ring 44 secured to the casting 14. The central portion of this casting is 70 bulged outwardly and is provided with a slide 46 and is also provided with an opening in which an elbow 48 is secured. Secured to the outer end of this elbow is a 75 spout 50 for introducing material into the 80 casing for treatment. The tubes 11 are held in fixed position at the rear by the head 12, while at the front the greater portion of the tubes are supported from the few longer tubes 16 by means of a plate 52 provided with holes 85 for the passage of the tubes. As shown in Fig. 5, the casing 32 preferably consists of two sheet metal cylindrical members one 90 around the other and between which a layer of asbestos is placed. As shown in Figs. 4 95 and 6, the casing at any convenient place may be provided with a removable closure. To provide for this closure a hole is made in the casing and an annular member 54 is secured to the material surrounding this hole 100 by bolts 56. The inner marginal portion of the member 54 is depressed and is provided with an annular groove 58 and with a flanged portion 60. A cover 62 lined with asbestos packing 63 has its periphery turned downwardly to engage packing 64 placed in the groove 58 and is secured in place by screw-bolts 66 whose heads are received in depressions in the cover and whose screw-threaded portions engage screw-threaded holes in the 105 110

flange 60. In order to prevent the material which is being treated from sticking to the tubes a cleaning device is provided. This device in the embodiment shown consists of 5 two cell-like members 68 having walls which rest upon the upper sides of the tubes 11 to act as scrapers, the cells preferably being of the same shape as that of the tubes. The tubes have been shown as diamond shape, but 10 it will be understood that they may be made of any other suitable shape. The two cell-like members 68 are spaced apart a distance from each other less than half the length of the tubes 11, so that they can be reciprocated along these tubes for the entire length thereof and they are connected by a number of bars 70, as will be understood from Figs. 5 and 7. In order to reciprocate the members 68 the mechanism now to be described is 15 provided. As shown in Fig. 2, a sprocket gear 72 is secured to the shaft 38. A sprocket chain 74 runs around the sprocket gear 72 and around a sprocket gear 76 secured to a shaft 78 whereby the latter is rotated. As 20 shown in Fig. 9, the shaft 78 is mounted in bearings 80 and 82 formed in a housing 83 which is provided with a removable top 84. Loosely mounted on the shaft 78 are two oppositely-disposed bevel gears 86 and 87 25 having clutch projections adapted to be alternately engaged by a clutch member 88 splined on the shaft 78. The gears 86 and 87 mesh with a gear 90 at diametrically opposite sides thereof. The gear 90 is secured to a shaft 30 92 to which is also secured a gear 94 meshing with a gear 96 rotatable on a stub shaft 98 carried by the housing. Secured to the hub of the gear 96 is a wheel 100 which has a recessed groove 102 therein. Two bolts 104 35 and 106, which may carry rollers as shown, are secured by their heads in this groove and they may be adjusted to any desired position upon loosening the nuts with which they are provided. An arm 108 is pivotally attached 40 at its lower end to the housing 83 by means of a bolt 110. A rod 112 is pivotally attached to the upper end of the arm 108, and this rod passes slidably through the two branches of a yoke member 114 which is rockingly 45 attached to the housing 83 by a bolt 116. The rod 112 is surrounded by a coiled spring 118 which is interposed between the upper branch of the yoke 114 and a cotter pin 120 passing through the rod. The arm 108 is provided 50 with an offset projection 122 which during the operation of the machine is alternately struck on its opposite sides by the bolts 104 and 106 as the direction of rotation of the gear 96 and wheel 100 is changed. In order 55 to shift the clutch member 86 it is provided with a circumferential groove in which a clutch fork 124 fits. This clutch fork has a stem 126 which extends into a slot 128 formed in the intermediate portion of the 60 arm 108. It is apparent that by the con-

struction just described the shaft 92 will be rocked back and forth. This shaft extends transversely across the top of the casing or cylinder and is supported at its outer end in a bearing 130 carried by a support 132. 70 Secured to this shaft are two drums 134 and 136 upon which are wound respectively a few turns of cables 138 and 140 which at the front of the machine engage sheaves 142 and 144, whereby their direction is changed in 75 order that they may pass through the front wall of the casing and be secured to the scraper device. The other portions of the cables 138 and 140 extend rearwardly and first engage sheaves 146 and 148 and then engage sheaves 80 150 and 152 respectively, whereby their direction is changed in order that they may pass through the rear wall of the casing and be secured to the scraper device. It will be understood that the cables pass snugly 85 through openings in the end walls of the casing so as to make a substantially air-tight fit.

The operation and advantages of my invention will be obvious in connection with the 90 foregoing description. The material to be treated is fed into the front of the casing through the spout 50 and as it passes progressively toward the rear it is continually lifted by the flights 40 as the casing rotates and is dropped repeatedly upon the tubes 11. These tubes are preferably arranged in staggered relation in a plurality of rows, as shown in Fig. 5, so that the material falls in a sinuous path between the tubes and is subjected to 100 the influence of the heating or cooling agent which is passing through the tubes. The cleaning or scraping mechanism prevents any of the material from remaining on the tops of the tubes whereby scorching, injurious 105 chilling or clogging is avoided. The shaft 78, as will be apparent from Fig. 2, is driven by the same source of power that rotates the casing, so that the clutch member 88, which is splined on this shaft, as shown in Fig. 9, 110 will rotate continuously therewith. When the clutch member 88 is at the right as shown in this figure, it engages the gear 87, whereby the gear 90 is rotated in one direction and when this clutch member is moved toward 115 the left it engages the gear 86, whereby the gear 90 is turned in the other direction. The shaft 92 to which the gear 90 is secured is thus caused to rotate alternately in opposite directions, and by means of the drums secured 120 to this shaft, the cables 138 and 140 produce a reciprocation of the scraper members along the tubes 11. By means of the gears 94 and 96, the wheel 100, carrying the bolts 104 and 106, is caused to turn in opposite directions alternately so that opposite sides of the projection 122 are struck by the bolts. The provision of the slot 128 in the arm 108 permits a slight movement of this arm before the shifting movement of the clutch 125 130

member 88 occurs. The arm 108 and the rod 112 constitute the two members of a toggle and the spring 118 is under compression when the toggle members are passing over their dead center. As they pass beyond this position the expansion of the spring aids in forcing home the clutch member 88 so that the gears 86 and 87 are firmly clutched.

I claim:

- 10 1. Apparatus for drying or cooling material comprising a rotatable casing, a plurality of fixed tubes extending within said casing, said tubes serving to contain a temperature-changing agent, a cleaning device engaging the exterior of said tubes, and mechanism for reciprocating said cleaning device and rotating said casing from the same source of power.
- 15 2. Apparatus for drying or cooling material comprising a rotatable casing, a plurality of fixed tubes extending within said casing, said tubes serving to contain a temperature-changing agent, means for successively lifting the material and dropping it upon the top 25 of said tubes, a cleaning device engaging the exterior of said tubes, and mechanism for reciprocating said cleaning device.
- 30 3. Apparatus for drying or cooling material comprising a rotatable casing, a plurality of fixed tubes extending within said casing, said tubes serving to contain a temperature-changing agent, a cleaning device engaging the exterior of said tubes, a cable extending through the opposite ends of said casing and 35 attached to said cleaning device, and means for moving said cable alternately in opposite directions to reciprocate said cleaning device.
- 40 4. Apparatus for drying or cooling material comprising a rotatable casing, a plurality of fixed tubes extending within said casing, said tubes serving to contain a temperature-changing agent, a scraping device engaging the exterior of said tubes, cables extending through the opposite ends of said casing and 45 attached to said scraping device, drums around which said cables pass, a shaft to

which said drums are secured, and means for rocking said shaft to cause reciprocation of said scraping device.

5. Apparatus for drying or cooling material comprising a casing, means for rotating said casing, a plurality of fixed tubes extending within said casing, said tubes serving to contain a temperature-changing agent, a platelike member having openings through 50 which said tubes pass respectively with the upper margins of said openings resting upon the upper surfaces of said tubes for producing a scraping action, and mechanism for reciprocating said platelike member.

6. Apparatus for drying or cooling material comprising a casing, means for rotating said casing, a plurality of fixed tubes extending within said casing, said tubes being angular in cross section and serving to contain 55 a temperature-changing agent, a platelike member having corresponding angular openings through which said tubes pass respectively with the upper margins of said openings resting upon the upper surfaces of said tubes for producing a scraping action, and mechanism for reciprocating said platelike member.

7. Apparatus for drying and cooling material comprising a casing, means for rotating said casing, a plurality of fixed tubes extending with said casing, said tubes serving to contain a temperature-changing agent, two platelike members having openings through 75 which said tubes pass respectively with the upper margins of said openings resting upon the upper surfaces of said tubes for producing a scraping action, connecting means between said platelike members for holding them spaced from each other at a distance less than half the length of said tubes, and mechanism for reciprocating said platelike members.

In testimony whereof I hereunto affix my signature.

ALEX G. HUHN.
